(57) **CLAIM**

The ornamental design for a jar sealer, as shown and described.

DESCRIPTION

FIG. 1 is a front perspective view of a jar sealer, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an exploded view of FIG. 1; and,

FIG. 10 is an alternate perspective view of the jar sealer's elements separated from the pump for ease of illustration. The broken lines in the drawings illustrate the portions of the jar sealer, which form no part of the claimed design.
